DOOR CLOSER

Filed June 1, 1932

UNITED STATES PATENT OFFICE

WALTER F. FOSTER, OF SAN FRANCISCO, CALIFORNIA

DOOR CLOSER

Application filed June 1, 1932. Serial No. 614,660.

The present invention relates to door closers of the spring actuated type.

The principal objects of the invention are to provide a closer which is adapted for concealment in the door or door frame, and which operates with a steady uniform motion with sufficient force to completely close the door but without causing undue slamming. Another object is to provide a closer which is adaptable, by a simple change in assembly, for either light or heavy doors. A further object is to provide a spring of sufficient length in proportion to the extent of its flexing; so that its force is not materially reduced as the door approaches closed position, and so that the elastic limit of the spring is not approached at any time, resulting in long life. Still further objects are to provide a convenient and accessible adjustable take up for the fixed end of the flexible tension member, and an adjustment for the tension of the spring.

Other objects and advantages of the invention will become apparent from the following specification, which should be read with the understanding that changes, within the limits of the claims hereto appended, may be made in the form, construction and arrangement of the several parts, without departing from the spirit of the invention as defined in said claims.

A preferred embodiment of the invention will now be described with reference to the accompanying drawing, wherein,

Fig. 1 is a horizontal section showing a door and door frame connected by my closer.

Fig. 2 is a vertical section taken on the line 2-2 of Fig. 1.

Fig. 3 is a vertical sectional detail illustrating a modified form of the mechanism shown in the upper right hand corner of Fig. 2.

Fig. 4 is a horizontal section on the line 4-4 of Fig. 2, the springs shown in Fig. 2 being omitted for the sake of clearness.

Referring more particularly to the drawing, the reference numerals 5 and 6 designate the two members of a door and door frame assembly, connected by a hinge 7. For purposes of this description, the member 5 will be referred to as the door and 6 as the frame, but said members are to be regarded as interchangeable in so far as the installation and operation of my closer is concerned.

The closer comprises a casing 8 mortised into the frame 6 and containing the operating mechanism to be later described, and an anchor member 9 mortised into the door. A flexible tension member, preferably a chain 10, has one end secured to the anchor member 9 and the other end connected with the closer mechanism within the casing 8, by which it is placed under tension to close the door.

The anchor member 9 has a face plate 11, and is provided with an aperture 12 through which the end of the chain 10 is inserted. A pawl 13 is pivoted at 14 in a slot in the side of the anchor member, and has a notched end 15 adapted to engage a link of the chain. A flat spring 16 holds said pawl in engagement with said chain. The pawl is so shaped that the chain can be pushed into the aperture 12 of the anchor member, but cannot be withdrawn therefrom except by inserting a flat bladed instrument (not shown) beside said chain and pressing the pawl out of engagement therewith. This construction provides simple means for assembling the chain with the anchor member and for adjusting the effective length of said chain.

The anchor member is first inserted in the door with the chain removed, and the end of said chain is then pushed into the aperture in said anchor member to the desired point, the pawl automatically locking it therein. If the chain is too long, it can be shortened merely by pushing in until the pawl engages the next link; if too short, the pawl can be released by the insertion of the flat bladed instrument re-

ferred to above, and the chain withdrawn one or more links.

The casing 8, inserted in the door frame 2, has a face plate 17 and a vertical cylindrical guide barrel 18, preferably connected with said face plate by a rib 19. A spindle 20 is rotatable in said guide barrel and has an end thrust bearing 21 at the upper end thereof. The upper end of the spindle has secured 10 upon it two sprockets 22 and 23, one above the other, operating within a chamber 24 in the upper portion of the casing 8. The upper sprocket 22 engages the chain 10, said chain entering the chamber 24 through an 15 aperture 25 in the face plate 17 and being held in engagement with said sprocket 22 by the side wall of the casing.

The lower end of the spindle 20 is provided with steep pitched threads 26, which engage a 20 nut 27 slidable in the barrel 18. A helical spring 28, shown only in Fig. 2, is housed within said barrel, and forces the nut 27 downwardly. The lower portion of the nut has a tenon 29 which fits slidably in a slot 30 25 in a plug 31, the latter being screwed into the lower end of the barrel 18 and locked in position by a set screw 32. The threads 26 are so formed that, when the door is opened and the chain 10 is pulled outwardly, the consequent rotation of the spindle 20 causes the 30 nut 27 to rise, compressing the spring 28. The expansion of said spring, forcing the nut down, rotates the spindle in the reverse direction, thereby drawing in the chain and 35 closing the door. The engagement of the tenon 29 with the slot 30 in the plug 31 prevents the nut from turning, the length of said tenon being so proportioned that it does not rise entirely out of said slot even upon maximum movement of the chain. The compression 40 of the spring can be adjusted by screwing the plug 31 up or down.

In order to maintain adequate engagement between the chain 10 and the sprocket 22, I 45 provide a second pair of sprockets 22' and 23' in the rear portion of the chamber 24, and an endless chain 33 surrounding and engaging both lower sprockets 23 and 23'. The end of the tension chain 10 is attached to the end- 50 less chain 33, preferably by having the pins 34 of several of its endmost links extend continuously through the links of the endless chain. The tension chain 10 is thus forced, by its attachment to the endless chain 55 33, to follow around and engage the upper rear sprocket 22'.

When the device is to be used upon a heavy door, the rear sprockets 22' and 23' are secured upon a spindle 20', which is rotatable 60 in a guide barrel 18' similar to the barrel 18. Said spindle has a thrust bearing 21', a threaded end 26', a nut 27', a spring 28', and said nut has a tenon 29' engaging a slot 30' in a screw plug 31' locked by a set screw 32', all these parts being identical in construc- 65

tion and operation to the corresponding parts associated with the barrel 18. Both spindles 20 and 20', therefore, are rotated simultaneously during the movement of the door, and both springs exert a closing force thereon. 70

The rear guide barrel 18' however, is removable from the casing 8, being secured thereto by a threaded connection 35 at its upper end and a clamp 36 connecting it with the front barrel 18. When the device is to be used upon a light door, the rear barrel 18' and all its interior parts are removed. A plug 37, Fig. 3, is screwed into the casing 8 in place of said barrel 18', and said plug has an upstanding stud 38 upon which the 80 sprockets 22' and 23' are rotatably mounted. In this modification, the sprockets 22' and 23' function merely as idlers to guide the chains 10 and 33. Thus the same casing 8 is used for both light and heavy door closers; 85 for light doors, the rear barrel 18' and its associated parts are omitted, but for heavy doors these members are attached, thereby doubling the effective closing force of the device. This utilization of the same casing for 90 both types makes for economy in manufacturing.

It is to be noted that the total movement of the nut is relatively small in proportion to the length of the spring. The spring, 95 therefore, exerts practically the same force throughout its entire range of movement, and is not weakened by being stressed beyond its elastic limit. Moreover, the friction of the nut upon the threaded portion of the spindle 100 acts as a governor to prevent too rapid closing and slamming of the door. These two effects, viz:—the almost constant force of the spring and the governor action of the screw 105 and nut, combine to produce a steady pull on the chain resulting in a smooth but positive closing of the door.

The device is entirely concealed when the door is closed and, being positioned in the rear edge of the door and the adjacent jamb 110 of the frame, is inconspicuous when the door is open. The effective length of the chain can be readily adjusted after the device is installed to accommodate it to hinges of various width, and within certain limits, to vary the 115 tension of the spring. Further adjustment of said spring tension is accomplished by screwing the plug 31 up or down.

I claim:—

1. A door closer comprising a casing secured to one member of a hinge connected door and door frame assembly; an anchor secured to the other member thereof; a pair of sprockets mounted in said casing; an endless chain surrounding and engaging said sprockets; a second chain having one end connected with said endless chain and the other end secured to said anchor; and resilient means associated with one of said sprockets 125

for rotating it in a direction to close the door.

2. A door closer comprising a casing secured to one member of a hinge connected 5 door and door frame assembly; an anchor secured to the other member thereof; a pair of sprockets mounted in said casing; an endless chain surrounding and engaging said sprockets; a second pair of sprockets axially 10 aligned with and adjacent to the first pair; a second chain having one end secured to said anchor and its other end secured to said endless chain, said second chain engaging said second pair of sprockets; and resilient 15 means associated with one of said sprockets for rotating it in a direction to close the door.

3. A door closer comprising a casing secured to one member of a hinge connected door and door frame assembly; an anchor 20 secured to the other member thereof; a rotatable spindle having a threaded portion within said casing; a nut engaging the threads of said spindle; a movable adjusting member having sliding engagement with said nut to 25 prevent the latter from turning; means for locking said adjusting member; a spring bearing resiliently against said nut for moving it axially upon said spindle to rotate the latter; and a flexible connecting member en- 30 gaged by said spindle and moved longitudinally by the rotation thereof, one end of said flexible member being attached to said anchor.

4. A door closer comprising a casing se- 35 cured to one member of a hinge connected door and door frame assembly; an anchor secured to the other member thereof; a rotatable spindle having a threaded portion within said casing; a nut engaging the threads of said spindle, said nut having a 40 projecting tenon at one end; a threaded plug axially aligned with said nut, said plug being screwed into said casing and provided with a slot having sliding engagement with said 45 tenon to prevent rotation of said nut; a spring bearing resiliently against said nut for moving it axially upon said spindle to rotate the latter; and a flexible connecting member engaged by said spindle and moved 50 longitudinally by the rotation thereof, one end of said flexible member being attached to said anchor.

5. A door closer comprising a casing se- 55 cured to one member of a hinge connected door and door frame assembly; an anchor secured to the other member thereof; a pair of guide barrels associated with said casing, one of said barrels being removable; a rotatable threaded spindle in each barrel; a 60 nut threaded upon each spindle, said nuts being slidable but non-rotatable within said barrels; springs within said barrels for moving said nuts, thereby rotating said spindles; and a flexible connecting member engaged 65 by said spindles and moved longitudinally

by the rotation thereof, one end of said flexible member being attached to said anchor.

6. A door closer comprising a casing secured to one member of a hinge connected 70 door and door frame assembly; an anchor secured to the other member thereof; a sprocket mounted in said casing; an endless chain surrounding said sprocket; guide means for keeping said chain in engagement with 75 said sprocket; a flexible tension member having one end connected with said chain and the other end secured to said anchor; and resilient means associated with said sprocket for rotating it in a direction to close the door.

7. A door closer comprising a casing secured to one member of a hinge connected door and door frame assembly; an anchor secured to the other member thereof; a sprocket mounted in said casing; an endless chain surrounding said sprocket; guide means for keeping said chain in engagement with 80 said sprocket; a flexible tension member having one end connected with said chain and the other end secured to said anchor; a rotatable threaded spindle upon which said sprocket is fixed; a slidable non-rotatable nut threaded upon said spindle; and a helical spring surrounding said spindle and acting 85 against said nut for rotating said spindle and sprocket in a direction to close the door.

8. In a door controlling device wherein a spring tensioned flexible member controls the movement of the door: an anchor member for engaging one end of the flexible member and having an aperture for the insertion of said flexible member therethrough to any desired extent, said anchor member having means for automatically locking said flexible member against withdrawal therefrom, whereby the spring tension of the flexible member may be varied in its control of the door movement.

9. In a door closing device wherein a flexible member secured at one end to a spring tension means controls the movement of a door relative to its frame: an anchor member for securing the other end of the flexible member, said anchor member being recessed for reception of the flexible member therein to any desired degree, and a locking member carried by said anchor member for engaging said flexible member, said locking member cooperating with said recess to permit free insertion of said flexible member thereinto and automatically locking said flexible member against outward movement relative to said anchor member, whereby the spring tension of the flexible member may be varied in automatically closing the door.

10. In a door closing device wherein a flexible chain is secured at one end to a spring tension means to control the movement of a door element relative to a door frame element: an anchor member for securing the opposite end of said chain to one of said ele- 125
